UNITED STATES PATENT OFFICE.

HUGH O. AMES, OF NEW ORLEANS, LOUISIANA.

STEAM-TRAP.

SPECIFICATION forming part of Letters Patent No. 226,951, dated April 27, 1880.

Application filed January 28, 1880.

To all whom it may concern:

Be it known that I, HUGH O. AMES, of New Orleans, parish of Orleans, and State of Louisiana, have invented a new and useful Improvement in Steam-Traps, of which the following is a specification.

The invention consists in combining with a vibratory arm carrying a water-receiver a side-apertured hollow trunnion, a discharge-pipe, a jacketed standard, and an outlet-pipe, as hereinafter described.

In the accompanying drawings, Figure 1 is a sectional plan view of my improved trap in the position for discharge of water; and Fig. 2 is a vertical section on line xx of Fig. 1, the apparatus being in position for receiving water.

Similar letters of reference indicate corresponding parts.

The tube or hollow arm h is supported by its hollow trunnions b e in fixed standards a a' . At one end of arm h is attached the receiver A , that is preferably a hollow sphere, and at the other end of arm h is a weight, B , which is sufficiently heavy to overbalance the receiver A and retain the latter in the position shown in Fig. 2 until it is filled with water to the extent required.

The steam-pipe to be drained is connected to the trunnion b at the standard a . The trunnion e is closed at the outer end and is provided with side openings, and the trunnion e' is formed with a jacket around the trunnion e , which has openings 1, to coincide with the openings in the trunnion when the receiver falls, and also communicates by suitable openings with the discharge-pipe m . These devices constitute a valve that is opened and closed by the vibration of the arm h .

From the back of trunnion e a pipe, d , passes through the arm h into the receiver A , and 40 terminates near the bottom thereof.

In operation the water enters through the trunnion b , and passes, by pipe h , to the receiver A , as indicated by the arrows, until sufficient water has accumulated to overbalance the 45 weight B , and the receiver falls and opens communication with pipe m . The water then goes out by pipe d , trunnion e , and pipe m , and is succeeded in the receiver A by steam until the weight B again restores the receiver 50 to its raised position.

The vibration of the arm h is limited by a stop, l , that is fixed beneath the arm, and the trunnions will be fitted with steam-tight packings.

The weight B is preferably a hollow sphere containing shot.

This construction furnishes a steam-trap which will act to discharge more or less frequently, as required, and remain in constant 60 operation, if necessary.

Having thus described my invention, I claim as new and desire to secure by Letters Patent—

In steam-traps, the combination, with the 65 vibrating arm h , carrying the water-receiver, of the hollow trunnion e' , having side apertures, the discharge-pipe d , jacketed standards a a' , and pipe m , substantially as shown and described.

HUGH OSWALD AMES.
